AUTOMATIC TRAFFIC SIGNAL SYSTEM

Francis J. Buechel, Jr., Rochester, N. Y., assignor, by mesne assignments, to Automatic Signal Corporation, a corporation of Delaware

Application May 2, 1928, Serial No. 274,499

12 Claims. (Cl. 177—337)

This invention relates to improvements in automatic traffic control signals.

The primary object of this invention is the provision of an improved automatic traffic signal device adapted to be used at the intersection of crossing streets for automatically regulating the traffic on the street according to the relative positioning of vehicular traffic upon the streets.

Advantage has been taken in the present invention of the fact that cars travel in group formation upon busy streets whereon the travel is regulated by means of traffic signal lights. In each group of vehicles it will be noted that they travel in rather uniform spaced relation along the street as they approach the intersection, and that there is a considerable space between the last car of a line or group and the advancing car of the next group coming down the street towards the intersection. The present invention utilizes this fact, and suitable control mechanism is used for shifting signals when the space interval between cars is such that the elapsed time required for spaced vehicles to pass a predetermined location adjacent an intersection will be sufficiently great to warrant a change of signals.

A further object of the invention is the provision of improved automatically operated traffic signal apparatus adapted to be placed at street intersections for regulating the changing of vehicle signals in accordance with the amount of vehicular travel and relative time spacing of the same upon the streets; the improved apparatus being entirely automatic in operation and embodying means for changing the signals after minimum and maximum periods of time, depending whether there is little or much vehicular traffic on the streets.

Other objects and advantages of this invention will be apparent during the course of the following detailed description.

In the accompanying drawings, forming a part of this specification, and wherein similar reference characters designate corresponding parts throughout the several views,

Figure 1 is a diagrammatic representation of the wiring of the improved traffic signals and switches therefor, showing the control arrangement for the signals in position for operating the green lights or "go" signals on the east and west streets, and the red or "stop" signals on the north and south streets.

Figure 2 is a diagrammatic representation of the details illustrated in Figure 1, with the position of parts as they are about to reverse, that is,

for travel of vehicular traffic across the intersection on the north and south streets.

Figure 3 is a fragmentary view, partly diagrammatic, and in side elevation, of the control mechanism for the improved automatic traffic signal arrangement.

Figure 4 is a plan view of an electro-magnetic operating apparatus for the control mechanism.

Figure 5 is a sectional view taken substantially on the line 5—5 of Figure 3.

Figure 6 is a sectional view taken through a vehicle operated street switch.

In the drawings, wherein for the purpose of illustration is shown only a preferred embodiment of the invention the letters A and B may respectively designate intersecting east and west, and north and south streets, as shown in Figures 1 and 2 of the drawings. Lamp signals 69 and 70 may be placed at the opposite sides of the intersection, at the eastern and western sides on the street A. Similarly, lamp signals 71 and 72 may be placed on the street B, at the north and south sides of the intersection. These signals are of the two lamp type; the green light preferably being nearest the curb, and a red light of each being remote from the nearest curb. Other lighting arrangements may be provided, if desired, and indeed these signals may be mechanically operated if desired. On the right sides of the street A at opposite sides of the intersection, looking in the direction of travel of traffic towards the intersection, street switches 73 and 74 may be placed, and in similar locations on the street B, street switches 75 and 76 may be placed on the northern and southern sides of the intersection. These street switches are adapted to cooperate in connection with the control mechanism of the invention subsequently described, in automatic regulation of the lights of the signal lamps 69 to 72 inclusive. Dummy policemen 77 may be placed in the middle of each of the streets at each side of the street intersection, to insure that vehicular traffic will all pass over the street switches as the vehicles approach the street intersection.

In Figure 6 is shown a longitudinal section of one of the street switches, it being understood that all of the street switches 73 to 76 inclusive embodies the same construction. The length of the switches are arranged transverse or at right angles to the run of the street, and each includes a switch box 78^a sunk in the street, and providing a compartment therein normally closed by a movable plate or cover 78, the upper surface of which is arranged to lie flush with the street surface. The switch box 78^a is provided

with shoulders 82 to limit the extent to which the plate 78 may be pressed into the box compartment. Normally spaced contacts 79 and 80 are carried on the facing surfaces of the cover 5 78 and box 78^a respectively, in insulated relation thereto, and connected in circuit arrangement with the signal lamps in a relation to be subsequently described. Springs 81 hold the top plate or cover 78 so that the contacts are spaced from 10 each other, and these springs have sufficient strength to allow only the excessive weight of an automobile to cause engagement of the contacts 78 and 80.

A control unit C is provided for regulating the 15 opposed travel of traffic on the streets A and B in a minimum or a maximum time, depending upon the amount of vehicular traffic on the street and the maximum time which it shall be allowed to travel on any one street. This control mechanism C includes a frame work which is only 20 partially shown, including upper and lower spaced stationary platforms D and E. A vertically positioned screw or spirally grooved shaft 1 has a bearing at its upper and lower ends in 25 the platforms D and E, as shown in Figure 3 of the drawings, and the spiral groove therein extends from end to end and is continuous. A prime mover or motor 45 is provided, having a 30 geared connection 45^a with a drive shaft 2 arranged transversely below the lower end of the 35 groove shaft 1 and below the platform E; bevel or miter gears 3 being provided for gearing the drive shaft 2 with the groove shaft or screw 1 for drive of the latter. Rods 4, 5, 6 and 7 are 40 supported in parallel relation with the grooved shaft 1, in uniformly spaced relation thereabout, bearing at their upper and lower ends in the 45 platforms D and E for oscillation. The upper ends of said rods extend above their upper bushings or bearings in the top platform D and are there 50 provided with collars 8 which prevent the longitudinal moving of the said rods with respect to their platforms D and E. Trips or tracers 9, 10, 55 11 and 12 are vertically slidable upon the rods 4, 5, 6 and 7 respectively, as shown in Figures 1, 3 and 5 of the drawings. Each of these trips is 60 provided with a radially disposed pin 13 which projects radially into the groove of the shaft or screw 1 and is removable therefrom by reason of circumferential movement of the tracer or trip which respectively carries the pin. These 65 pins 13 extend through the cylinder of the trips or tracers, into sliding engagement in vertical slots or grooves 13^a which are provided in the 70 rods for the respective pins 13. The pins 13 operating in the grooves of these rods 4, 5, 6 and 7 prevent the cylinder bodies of the tracers or trips from turning on the rods, and for a purpose 75 which will be subsequently described.

The upper ends of the rods 4, 5, 6 and 7 extend 80 above the top surface of the platform D and are there provided with rigid radially extending arms 14, best shown in Figure 4 of the drawings. On the top surface of the platform D are provided 85 solenoids 19, 20, 21 and 22, which respectively slidably support armatures 15, 16, 17 and 18. These armatures are respectively pivoted at their outer ends to the outer ends of the arms 14 of the rods 4, 5, 6 and 7 in order that when the 90 solenoids are energized the respective armatures will be drawn in and the rods 4, 5, 6, and 7 turned slightly on their axes. Inasmuch as the trips or tracers 9, 10, 11 and 12 are slidably positioned upon these rods against rotation, it is apparent 95 that the pins 13 thereof will be disengaged from

the groove in the upright shaft or screw 1 when the solenoids are energized, to permit said trips or tracers to drop on the rods on which they are slidably positioned, to the bottom platform E. Springs 23, shown in Figure 4 of the drawings, hold the arms 14 against stop pins 24, and in this position, with the solenoids de-energized the trips will have their pins 13 engage in the groove of the screw or shaft 1.

In spaced relation with the rods 4, 5, 6 and 7, 10 and in respective diametrically opposed relation from the screw or shaft 1, other rods 25, 26, 27 and 28 are provided, as shown in Figure 5 of the drawings, and elsewhere, which are parallel with the shaft 1 and the rods 4 to 7 inclusive, and 15 bear at their upper and lower ends in the platforms D and E for reciprocation in said platforms, so that the upper ends thereof may be extended above the upper surface of the platform D for operation of certain switches for a purpose 20 to be subsequently described. These last mentioned rods respectively support adjustable knobs 30, 31, 32 and 33, which are cylindrical in formation and are adjustably clamped to the respective rods by means of set screws 32^a, more particularly shown in Figure 3 of the drawings. Each 25 of these knobs is provided with an annular flange 33^a thereabout, which the trip or tracer slidable on the adjacent rod is adapted to engage when the tracer has been elevated by the groove screw 30 1 sufficiently to engage the flange 33^a, and thus to force the respective rod 25, 26, 27 or 28 at its upper end through the platform D for switch closing purposes, to be subsequently mentioned. At the upper ends the rods 25 to 28 inclusive 35 are each provided with an enlarged insulation head 36 which holds the rods from falling thru the platform D and serves the additional purpose of insulating the switches 37, 38, 39 and 40 from the respective rods 25, 26, 27 and 28. 40 These switches 37 to 40 inclusive are mounted on the top of the platform D and are each composed of two spring members 41 and 42, mounted at an end of each in an insulation block 43. The rods 25 to 28 inclusive are so respectively 45 mounted with the switches 37 to 40 inclusive that when the said rods are elevated the upper insulated heads thereof will engage the lower switch arms 41 of the respective switches, and press the same into engagement with the upper switch arm 50 42 for closing a circuit for purposes which will be subsequently described.

As part of the control mechanism, a cam 44 is provided, having five grooves 44^a, 44^b, 44^c, 44^d, and 44^e therein. The grooves 44^a and 44^b extend 55 about 90° around the circumference of the cam 44, in different planes. The grooves 44^c and 44^d extend about 180° about the circumference of the cam 44 in different planes. There are two of the grooves 44^e, of crescent shape formation, each 60 slightly less than 180°, and located in the same plane. These cam grooves are more particularly shown in the sectional views thru the cam 44, in Figure 1 of the drawings. The cam 44 is keyed upon a shaft 2^a. Rotatable and slidable on this 65 shaft 2^a is a sprocket wheel 47, which is connected with a sprocket wheel 47^a keyed on the shaft 2 by means of a chain belt 46. The sprocket wheel 47 has a clutch part 48 thereon adapted to mesh with a clutch part 48^a keyed on the 70 shaft 2^a. The clutch for keying the cam 44 on the shaft 2^a includes a clutch lever 50 pivoted at 75 intermediate its ends; a spring 49 being provided for normally urging the clutch lever 50 against a stop 52, so as to disengage the clutch 75

parts 48 and 49, as shown in Figure 3 of the drawings. The clutch lever 50 is really an armature for the electromagnets 51, which are mounted upon a suitable frame 51^a, and in a circuit for the purpose of attracting the armature to rotate the cam 44 in order to shift the signals on the streets at an intersection, in a relation to be subsequently described.

Plungers or rods 54 are slidably positioned upon a supporting block 55 above the cam 44, having ends which extend for operation in each of the grooves 44^a, 44^b, 44^c, 44^d and 44^e of the cam. These plungers are held against the cam 44 by means of springs 55^a. At its upper end above the block 55 each of the plungers has an insulation tip 57, which is annularly grooved, and which receives the movable end of a switch arm 64. Switches 58 and 59 are respectively operated by the plungers as controlled in the grooves 44^a and 44^b; switches 60 and 61 are controlled by the plungers 54 as operating in the grooves 44^c and 44^d, and a switch 62 is operated by the plunger 54 which cooperates in the groove 44^e. Each of the switches 58, 59, 60 and 61 includes upper and lower spring switch arms 63 and 65, mounted on an insulation block 68, and between which the switch arm 64, which is also carried by the block 68, operates to alternately engage and close circuits through the switch arms 63 and 65. The switch 62 includes the top spring switch arm 66 secured in an insulation block 68, and a second switch arm 67 mounted on this block 68, and at its opposite end connected with the insulation cap 57 of the slide plunger 54 which operates in the grooves 44^e of the cam 44, as shown in Figure 1 of the drawings.

As part of the operating circuit there are five sets of electro-magnets which cooperate in circuit regulating relation with the solenoids 19 to 22 inclusive. These sets of electro-magnets comprise a set consisting of two electro-magnets 83 having upper and lower armatures 84 and 85 cooperating therewith; the upper armature when attracted by the electro-magnets 83 engaging four contacts 86, 87, 88 and 89. The bottom armature 45 has one contact 90 which it engages when attracted by the electro-magnets 83. The second set of electro-magnets 91 has also upper and lower armature 92 and 93 respectively, each of the same having one contact which it engages when attracted by a magnet. Thus the armature 92 has a contact 94 and the armature 93 has a contact 95. The third set of electro-magnets 96 has upper and lower armatures 97 and 98; the upper armature 97 having contacts 99 and 100 which are engaged when the armature 97 is attracted by the electromagnets 96. The lower armature 98 has a single contact 101 which is engaged when the lower armature is attracted by the magnets 96. The other set of electro-magnets 102 has also upper and lower armatures 103 and 104. The upper armature 103 has contacts 105 and 106 which are engaged when the armature is attracted. The lower armature 104 has a single contact 107 which it engages when the lower armature is attracted by the electro-magnets 102. Normally the armatures 84, 85, 92, 93, 97, 98, 103 and 104 are disengaged from their contacts, with the electro-magnets thereof de-energized, and the armatures held against stops 108 by means of springs 109 which individually actuate the same to move them away from the electro-magnets. Another set of electro-magnets 110 is provided, which are controlled by the switch 62 in a manner to be subsequently described, for shifting current

in a cooperative relation with the electro-magnets 83 as will be subsequently described. This set of electro-magnets 110 has a single armature 111 normally held in engagement with a contact 112 by means of a spring 113 when the electromagnets 110 are de-energized. When energized the electro-magnets 110 draw the armature 111 into engagement with another contact 114 provided therefor, and for a purpose to be subsequently described.

As before mentioned, the operation of the signal is dependent upon the elapsed time necessary for spaced vehicles traveling toward an intersection from the same direction to reach a predetermined point adjacent the intersection. When the group 15 of vehicles traveling on the street with the "go" signal are closely spaced as they approach the intersection the signal light will remain thus until the spacing of the vehicles at opposite sides of the intersection, on the street which has the "go" 20 signal set are such that a change is desirable in the signals. The travel of vehicles on a street may be so light and the vehicles so irregularly spaced thereon that it is desirable for the signal "go" to remain on for a minimum time. Also, it 25 may be desirable that a switch in signals occur if the travel of vehicles is so heavy on the street that after a maximum time a change in the signal lights should occur. The control mechanism takes care of all of these features. The control 30 parts may be conveniently divided into several parts as follows:—

One of the street controls may include the rod 4, its tracer 9, the rod 25, its knob 30, the switch 37, solenoid 19 and electro-magnet 96. 35

Another street light control may include the rod 5, with its trip or tracer 10, the rod 26 with its knob 31, the switch 38, solenoid 20 and electro-magnets 102.

A third control which may be conveniently 40 termed the minimum control, may include the rod 6, with its trip 11, rod 27 with its knob 32, switch 39, solenoid 21, and electro-magnets 91.

The fourth control which may be conveniently 45 termed the maximum control may include the rod 7 with its trip 12, rod 28 with its knob 33, switch 40, solenoid 22, and electro-magnets 83.

With the motor 45 running the drive shaft 2 is rotated and due to its geared connection, the shaft 1 is rotated. Normally the pins 13 of the 50 trips 9, 10, 11 and 12 engage in a groove of the shaft 1 and by reason thereof the trips 9, 10, 11 and 12 will elevate along their rods 4, 5, 6 and 7 respectively, until they engage the flanges of the knobs 30, 31, 32, or 33. The knobs 30 and 31 are fastened on the rods 25 and 26 at a certain height by means of thumb screws 32^a so that it will take the trips 9 and 10 the same time to rise from the bottom platform and reach said knobs, raising them slightly, and since they are fastened to the rods 25 and 26, elevating these rods and pressing the bottom members 41 of the switches 37 and 38, against the top arms 42 thereof, and closing said switches. The time elapsing for the climbing upward of the trips 9 and 10 on their rods is determined upon according to the time which elapses between the passing of cars over the street switches. At dull times of the day the minimum control establishes a minimum time that the signals are to remain on and off. For example, this 55 may be established at eight seconds, as determining the time between changes of signals, entirely independent of the extent of vehicular traffic. The knob 32 which forms parts of the minimum control is set at a certain height on the rod 27, 60

so that it takes the tracer or trip 11 eight seconds to rise from the bottom platform to the knob 32 and raise it slightly, to close the members of the switch 30, causing electricity to pass through the said switch. For various reasons it is desirable to limit the passing of traffic to a certain length of time, say thirty seconds independent of the extent of vehicular traffic. The maximum control has the knob 33 set at a certain height on the rod 28, so that it will take the tracer 12 thirty seconds to rise from the bottom platform and trip the knob 33 to raise the rod 28 sufficient to close the switch 40.

The closing of the circuits throughout the various solenoids, electro-magnets, and switches will be referred to during the description of the operation. A generator or source of current 115 is provided, from which positive and negative wires 123 and 117 respectively lead off into the wire system, and from these main wires 117 and 123 various branch circuits are provided to the different details of the system. Referring to the switch 58 which controls the red and green signal lights of the signal lamps 69 and 70, it will be noted that the member 64 of this switch 58 is connected to a positive wire 115 which branches off from the main positive wire 123. With the details as arranged in Figure 1 for travel of traffic on the east and west streets of the intersection, the center arm 64 is making contact with the bottom member 65 of the switch. This bottom member 65 is connected by the wire 116 to the green lamps of the signals 69 and 70; these lamps, as well as the red lamps of the signals 69 and 70 being supplied with negative current from the wire 117 as shown in the circuit. It is therefore obvious that with the switch 58 in this position the green lights will be illuminated and indicate to traffic the clear passage across the intersection on the street A, or in an east and west direction. The switch 59 controls the flashing of the green and red lamps on the signals 71 and 72 for controlling traffic on the north or south streets B across the intersection, and inasmuch as the center arm 64 of this switch is connected to the positive current wire 115, and is making contact with the upper switch arm 63, the red signal lamps of the signals 71 and 72 will be illuminated for stopping passage of traffic on the street B across the intersection. It is of course apparent that the switches 58 and 59 are thus positioned by reason of the riding of the plungers 54 on the cam 44 with respect to the grooves provided for these respective switches.

The switch 60 controls the flow of current into the system through the street switches 74 and 75. With the plunger 54 in the groove 44c of the cam 44, as shown in Figure 1, the center member 64 of the switch 60 is making contact with the bottom arm 65. This center member 64 of this particular switch is connected by a wire 119 to the solenoid 19 which forms part of the street control system, and the bottom member 65 of this switch is connected by a wire 120 to the street switch 74 on the street A. Negative current is supplied to the switches 74 and 75 thru the wire 117 as shown.

The switch 61 controls the flow of current through the switches 73 and 75. As shown in Figure 1, the plunger 54 of this switch 61 is operating in the groove 44d of the cam 44, and pulls the center member 64 down into contact with the bottom switch arm 65. The center member 64 of this switch is connected by a wire 121 with the solenoid 20, forming part of the street control mechanism. The top arm 63 is

connected by wire 126 with the switch 75, and the bottom arm 65 of this switch is connected by a wire 122 to the street switch 73. These switches 73 and 75 receive negative current from the wire 117 as shown in the wire connections. It will thus be noted that the street switches 73 and 74 are in an operative circuit for the street A on which traffic is now passing.

Referring further to the operation, with the knobs 30, 31, 32 and 33 of the control mechanism 10 C set in their proper position, and the street switches 73 and 74 in position to be closed by vehicular traffic in order to operate details of the control mechanism; the tracers 9, 10, 11 and 12, at the instant that the green lights flash in 15 the signals 69 and 70 all begin to rise simultaneously from the bottom platform E, inasmuch as the pins 13 thereof operate in the groove of the shaft 1. Every time that a vehicle passes over the street switch 74, contact is made and a circuit from this switch 74 closes thru the wire 117, wire 120, switch 60 in its lower position, wire 119, and solenoid 19. The solenoid 19 receiving positive current at all times from wire 123 becomes energized and draws in its armature 15, and by 20 reason of the arm connection 14 a slight turn is given to the control rod 4. The turn is sufficient to remove the pin 13 of the trip 9 from the groove of shaft 1, permitting the trip or tracer 9 to drop against the bottom platform E, from the 25 position to which it had climbed on the rod 4, prior to the time that the vehicle crossed the street switch 74. Every time that a contact is made in the switch 74, with the cam 44 set as shown in Figure 1, this operation will take place. 30

Similarly, when a contact is made in the other street switch 73 of the east and west street A, current flows through the wires 117 and 122 leading therefrom, to the closed portion (see Figure 1) of the switch 61, into wire 121 and into solenoid 20. This solenoid 20 receives its current from wire 123 at all times, and upon energization it draws its armature 16 thereinto, and through the arm 14, a slight turn is given to the rod 5, sufficient to remove the pin 13 of the 35 trip or tracer 10 from the groove of the shaft 1, and permitting the tracer 10 to drop to the bottom platform E, from the height to which it has elevated prior to the time that the vehicle passed over the street switch 73. Of course as soon as 40 the vehicle leaves the switches 73 and 74 the current is broken in the circuit therewith and the springs 23 will pull the solenoid-cores back into their position shown in Figure 4, and throw the pins 13 of the trips 9 and 10 into the groove 45 of the shaft 1, and the trips 9 and 10 again begin to rise upon their respective rods; it of course 50 being understood that the shaft 1 is rotating all 55 of the time.

So long as the total time required for each of 60 the tracers 9 and 10 to reach and slightly lift their respective knobs 30 and 31, is longer than the time which elapses between successive operations of the respective street switches by the rear of one car and the front of the next car 65 following, in the line of cars approaching the same, the said tracers or trips 9 and 10 will not reach their respective knobs 30 and 31. However, when the time interval of street switch operation by successive cars passing the signal 70 becomes greater than the predetermined time, the trips will operate against the knobs 30 and 31, for achieving the results mentioned.

Assuming that there is a large amount of traffic passing in both directions on the street 75

A. If the minimum control is set for eight seconds, and the traffic has been passing across the intersection on the street A for this length of time, the tracer 11 will reach and lift the knob 32, and inasmuch as the latter is fastened to the rod 27, said rod will be lifted and pressed against the member 41 of the switch 38, pressing against the top member 42, and thus closing this switch. The bottom switch arm 41 receives negative current from the wire 117, as shown in the operating circuit in Figures 1 and 2 of the drawings, and the contact in the switch 38 being made, the current will pass from wire 117, thru the switch 38, into wire 124, and into the set 5 of electro-magnets 91. Positive current is received by electro-magnets 91 from wire 125, switch contact 112, armature 111, and wire 123, energizing the magnets 91 and causing the armatures 92 and 93 to close against their respective contacts 94 and 95. Simultaneously with the energizing of electro-magnets 91, the solenoid 21 is energized, receiving negative current from wire 117, switch 38, wire 124, and positive current at all times from wire 123, as can be understood 10 from the diagrammatic wiring in Figure 1. Contact 94 is connected with the negative current wire 117, and the armature 92 engaging contact 94 will permit the negative current to pass into armature 92 and into wire 124, from which the 15 electro-magnets 91 and solenoid 21 now receive a supply of negative current. Remembering now that as soon as solenoid 21 became energized, the armature 17 was drawn in and the rod 6 slightly turned, removing the pin 13 of tracer 11 from the grooved shaft 1, and permitting the tracer 11 to drop to the bottom platform E, it is apparent that knob 32 and rod 27 fastened thereto will likewise be permitted to drop the distance they were raised, and the members 41 and 42 of 20 the switch 38 become disengaged, opening this switch and permitting the circuit through the switch 38 to open. However, in view of the negative current passing through the armature 92, the wire 124 is now receiving its negative current 25 thru engagement of this armature with the contact 94. Subsequent to this, if the vehicles passing on the street A in an eastward direction are successively spaced farther apart than will permit them to reach the switch adjacent the 30 intersection within a predetermined elapsed time and by which the street controls were set, the tracer 9 will have ample time to rise and reach its knob 30, and lift it slightly, causing the rod 25 keyed therewith to ride and press the bottom arm 41 of the switch 37 against the top arm 42 thereof. This of course happens because the street switch 74 was not operated soon enough by vehicular traffic to cause a trip of the tracer 9 prior to the time that it caused closing of the 35 switch 37. In this switch the bottom arm 41 receives negative current from wire 117, which passes into wire 126 and into the set of electro-magnets 96. Positive current is received by these electro-magnets from wire 125 through contact 112, armature 111, and lines 123, and energization of the electro-magnets 96 will cause the armatures 97 and 98 thereof to engage the respective contacts 99, 100, and 101 provided therefor, as shown in Figures 1 and 2 of the drawings, 40 45 50

Since armature 97 engages contact 99, negative current from wire 126 passes through armature 97 into contact 99, and into wire 127 and thus into wire 119, and into solenoid 19, which now becomes energized, inasmuch as it receives positive current from wire 123, at all times. The 55 60 65 70 75

contact 100 is directly connected with negative current supply wire 117, and inasmuch as armature 97 engages the same at this time, negative current passes to contact 100 into armature 97, and into wire 126, from which electro-magnets 5 now receive the negative current. Solenoid 19 now also receives its negative current from contact 100, inasmuch as the negative current from contact 100 passes through armature 97, and into contact 99 and wire 127, into wire 119 to this 10 solenoid 19. This extra source of negative electricity from contact 100 is now necessary, since as soon as solenoid 19 was energized, and rod 4 turned, the tracer 9 became disengaged with shaft 1 permitting it to fall to the bottom platform E, 15 and likewise permitting knob 30 and its rod 25 to drop and release the contacts of switch 37. Were it not that the negative current is now supplied from contact 100, the electro-magnets 96 and solenoid 19 would not remain in a state 20 of energization, as they now should.

A similar operation occurs when the spacing of the vehicles in the street A, passing westwardly over the intersection is such that the tracer 10 has ample time to rise and trip the 25 knob 31 before the next vehicle operates the street switch 73 to prevent such operation. Tripping of the knob 31 elevates the rod 26 and engages the contacts 41 and 42 of the switch 38, negative current then passing from wire 117, 30 through the closed switch 38 into wire 128 and into the electro-magnets 102, for energizing them. Positive current is of course received by these electro-magnets 102 from wire 125. Upon energization the electro-magnets will attract the 35 armatures 103 and 104 for engaging the contacts 105, 106, and 107 in their respective relations. The armature 103 engaging the contact 105, permits negative current to flow from wire 128 through the armature 103 into contact 105, and 40 45 50 55 60 65 70 75

through wires 129 and 121 into solenoid 20. This solenoid is energized, receiving positive current from wire 123. Contact 106 being directly connected with negative current wire 117, with the armature 103 engaging the same, the current will pass therefrom into wire 128, from which electro-magnets 102 now receive their negative current. Solenoid 20 now receives this negative current from contact 106, inasmuch as the negative current from contact 106 passes through wires 129 and 121 in the relation above described, and maintains the solenoid 20 energized; this being necessary since as soon as it was energized the rod 5 was turned and the tracer 10 permitted to drop, to disengage the contacts of the switch 38 through dropping of the rod 26. Thus, notwithstanding the opening of the switch 38 the electro-magnets 102 and solenoids 20 remain energized.

From the above it will be apparent that the 60 electro-magnets 91, 96 and 102 are now all energized, and attracting their respective armatures 93, 98 and 104 in engagement with the contacts 95, 101 and 107 respectively provided therefor. This permits current to flow from the wire 117 through these various armatures and contacts into electro-magnets 83, which now become energized, inasmuch as they receive positive current from the wire 125. It will be noted that all three sets of armatures 91, 96, and 102 must be energized with their contacts before negative current is permitted to enter the electro-magnets 83. Upon energizing of the electro-magnets 83, the armatures 84 and 85 will be attracted and closed into engagement with the contacts provided 70 75

therefor. The armature 84 engages the contacts 86, 87, 88 and 89, and the armature 85 engages the contact 90 provided therefor. Inasmuch as armature 84 is connected with the wire 117 for receiving negative current therefrom at all times, it is apparent that it will pass the same onto the contacts 86, 87, 88 and 89 upon energizing of the electro-magnets 83. From contact 86 the negative current goes into the wire 130, through electro-magnets 83, and solenoid 22, energizing the latter, and releasing its tracer 12 which has not yet reached the knob 33. Since contact 90 is directly connected with the positive current wire 123, current from this wire now passes thru contact 90, armature 85, wire 131, and into electro-magnets 51 which control the clutch of the cam 44, energizing the electro-magnets 51, and attracting the armature 50. This moves the clutch part 48 into engagement with the clutch part 48^a, and engages the clutch for keying the cam 44 to the shaft 2^a. The cam 44 now revolves, and makes nearly one-half of a revolution. During this turn the plunger 54 for the switch 62 will rise from the groove 44^c in which it reposed, towards the outer surface of the cam 44, until the switch members 66 and 67 of the switch 62 engage. The switch member 67 of said switch is directly connected to the positive current wire 123, and the current therefrom passes into the switch arm 66 and into the wire 132, and into electro-magnets 110, to energize the latter, inasmuch as they are connected to circuit 117. Electro-magnets 110 now draw the armature 111 thereof from contact 112 over to its other contact 114. This breaks the circuit thru the electro-magnets 83, 91, 96 and 102, and de-energize the same. All of the armatures of these electro-magnets 83, 91, 96 and 102 are now pulled by their springs 109 into engagement with stops 108, to their normal inoperative position, and it is thus apparent that the current thru the solenoids 19, 20, 21 and 22 will also be broken, permitting the rods 4, 5, 6 and 7 with their respective trips or tracers 9, 10, 11 and 12 to be pulled by springs 23 for a short arcuate movement, until the arms 14 engage the stops 24, engaging the pins 13 of these trips 9, 10, 11 and 12 in the groove of the shaft 1, and resetting the trips for movement along their respective rods.

50 When the armature 111 was shifted as above described upon energization of its electro-magnet, the current was broken in electro-magnets 83. This allows the armature 85 to disengage from contact 90. This breaks the current in electro-magnets 51, and the clutch disengages before the cam 44 makes a complete half revolution. The cam stops at a point where the plunger 54 of the switch 62 is still on the outer edge of the cam 44. However, armature 111 engaging contact 114 sends positive current to wire 131 and into electro-magnets 51, permitting the clutch to remain engaged and the cam 44 to finish its half revolution. As soon as the cam 44 finishes its half revolution the plunger 54 of the switch 62 drops into the abrupt end of one of the grooves 44^c, disengaging the switch arms of the switch 62. The positive current through the electro-magnets 110 is then broken and the armature 111 is pulled back against the contact 112 by means of the spring 113, breaking the current through electro-magnets 51 and permitting the clutch 48 to disengage and stop revolution of the cam 44.

70 The above operation of the cam 44 for a half revolution has now operated the plunger 54 of the switch 58 so that the center arm 64 engages

the upper arm 63, and as the upper arm 63 is connected by wire 133 through the red signal lamps of the signals 69 and 70, the latter are operated on the streets A for stopping travel of traffic thereon across the intersection. For the switch 59 the center arm 64 has been moved into engagement with the lower arm 65, by reason of the dropping of the plunger 54 of said switch into the groove 44^b, and as the bottom member 65 of this switch is connected by wire 134 to the green signal lamps on the signals 11 and 12, the latter are thus operated to indicate to traffic on the streets B that it may travel across the intersection. In the switch 58 the plunger 54 thereof has been elevated to the outer periphery of the cam 44, so that the center arm 64 now engages the upper arm 63 thereof, and as the upper arm 63 is connected by wire 135 to the street switch 76, the latter upon depression will operate a circuit through the switch 60 including the details above described. In the switch 61 the plunger 54 has been elevated to the outer periphery of the cam 44, to engage the center contact 64 with the arm 63, sending the current thru wire 136 to the street switch 75, so that upon depression of the latter the current will be closed thru the contacts of the switch 61 as thus engaged for operating details of the control mechanism in the cycle above described.

The signal now has completed one half of the cycle and it is ready for travel of traffic on the street B across the intersection. While the cam 44 is making its half revolution during the signal switching operation, it will be noted that for a short time the red lights are showing in all the signals 69 to 72 inclusive, by reason of the design of the cam groove 44^a and 44^b, which are only approximately 90° in length, so that during about a 90° travel of the cam 44 all of the red signals will be on which permits ample time for the vehicles and pedestrians who have started across the intersection to pass the signal before the switch in red and green signals takes place.

The above operation contemplates the condition where traffic on the streets having the right of way has crossed the street switches within the predetermined time so that the street controls have not been able to operate during the minimum period, but that sometime between the operation of the minimum control and before the expiration of the thirty-second maximum period, traffic has become so straggly as to permit a trip operation of switches 37 and 38 and a change in signals. Automatic periodic alternation of the right of way to the respective streets is determined by operation of the minimum controls when heavy traffic approaches the street intersection too late to reach the street switches before their controls have operated and before the minimum control has operated. However, if the vehicles passing along the street A are closely spaced so that the street switches 73 and 74 will be operated continuously, or at least one of them operated without permitting the trip operation of the switch 37 or 38 therefor, at the end of the thirty second period the tracer or trip 12 will reach the knob 33, and lifting the rod 28 will contact the arms 41 and 42 of the switch 40, for closing the latter. Inasmuch as its switch arm 41 is directly connected with the negative supply wire 117, this current will pass through the wire 130 into the electro-magnets 83, with the result that they will be energized. Negative current from armature 84 is sent through the contacts 86, 87, 88 and 89, which in turn delivers the cur-

rent to electro-magnets 83, 91, 96 and 102 respectively, engaging their armatures with their contacts, and thence to the solenoids 19, 20, 21 and 22, disengaging all tracers from the groove in the shaft 1, and the same operations follow as above described for a shifting in the signals. Thus if the maximum control is set for a certain time, and the traffic is greater than can pass in that time, the maximum control will cause an operation which will change the lights in the signals, regardless of the two street controls in the mechanism C.

Insofar as the signals are concerned, when there is no traffic on either street A or B, the right of way indication is given alternately from one street to the other, remaining on each street for a period of time equal to the time at which the minimum control is set, which is eight seconds. Thus, as soon as the right of way indication is given to a street, the trips or tracers of both of the street controls commence their upward movement. Since there is no traffic to actuate the street switches and thus cause a resetting of the street controls, which means a loss in its upward movement, they will reach their complete predetermined upward travel and thus cause an operation of their respective electro-magnets in, let us say, three seconds. But since the minimum control is so arranged in connection with the street controls that it also must have caused an operation of its respective electro-magnets, to effect a change in signals, no shifting in signals will have yet occurred. It will be remembered that as soon as the trips of the street controls begin their upward movement, the trip of the minimum control also begins its upward movement. Since the street controls have actuated their respective electro-magnets, it will only be necessary for the minimum control to cause an operation of its respective electro-magnets to cause a change in signals. Since the minimum control is set at eight seconds, this change in right of way indication will occur eight seconds after the previous change in signals, which will be five seconds after the street controls have completed their particular function. The same will then continue with the other streets, etc., alternately from one street to the other for periods of eight seconds each. The signals will operate in this manner so long as there is no traffic present on the street.

When an A street switch actuation is followed within eight seconds by a B street switch actuation nothing will happen so far as signal change is concerned. In this connection it must be remembered that the street which has the right of way also has its street switches connected with the street controls; the street switches of the other streets being disconnected. Any actuation of them does not produce any effect on the signal mechanism. It will be observed that the same street controls are used in operative relation with the street switches in both streets; said street controls being shifted from one set of street switches to the other set with the changing of the right of way indications. Thus, when the street switches of one street are connected with the street controls, the street switches in the other street are free and disconnected and it is obvious that if street A has the right of way any actuation of the street switches in street B will not produce any effect on the signalling mechanism. However, if during the time elapsed between the last actuation of the A street switch and the B street switch, a change in signals should

occur, giving the street B the right of way, then the actuation of the B street switch, since the B street switches are now connected with the street controls because of the street B now having the right of way, will reset its particular street control, giving it a fresh start in its upward movement.

Assuming that street A has the right of way indication, which is maintained as such on account of continuous closely spaced switch actuations on A street. If said actuations continue for thirty seconds, at the end of this period the maximum control will function, since it is set at thirty seconds. Notwithstanding the fact that the street controls have not operated their respective electro-magnets on account of the closely occurring A street switch actuations, there will be a change in signals. Since street A has the right of way its street switches are connected with the street controls; the street switches of street B being free and disconnected. Hence if actuation of a switch on B street occurs 15 seconds, let us say, after the first switch actuation on A street, nothing will happen to change the signalling, since the B street switch actuation 25 will have no effect.

If B street has the "green" or right of way indication, and there is no traffic on said B street, said right of way indication will remain on B street for a time equal to the time at which the minimum control is set, which is eight seconds. Therefore, if an actuation of an A street switch takes place while the "green" indication is given to B street, and consequently the "red" indication to A street, nothing will happen to change the 35 signals since the A street switches are free and disconnected from the street controls which are then in operative relation with the B street switches, since the latter has the "go" signal.

The advantages embodied in the present invention of connecting each switch separately to an operating mechanism are generally as follows:—

First.—Such an arrangement is particularly adapted for operation at intersections of main 45 streets or highways, where traffic is relatively heavy on both streets, whereas signals which have the switches in the same street connected to a single operating mechanism are useful only where a main street intersects with a subordinate street 50 and thus are not efficient controllers of traffic where two main streets intersect.

Second.—The operation of the signal is directly controlled by the density of traffic approaching each side of the street, effecting a more uniform 55 and accurate regulation of traffic and accomplishing this in a quicker and more efficient manner than is possible if the street switches were connected to one operating mechanism. In the present arrangement traffic must be relatively heavy 60 on at least one side of the street having the right of way indication to hold said indication, else a change in signals will occur. In signal arrangements where the street switches are connected to one operating mechanism a straggling car from 65 one side of the cross street, and then another straggling car from the other side occurring within the predetermined time will keep the right of way on said cross street. In the present arrangement cars must pass in a continued stream, 70 each within the predetermined time interval of the preceding car, from at least one side of the street to hold the indication on said street. A straggling car from one side and then another straggling car from the other side, even if within 75

the same predetermined interval of time of each other will not hold the right of way indication on said street. It is therefore seen that signals employing one operating mechanism for two street switches do not operate directly and uniformly according to the density of traffic on the street, as the present signal does.

It is apparent from the foregoing that a novel traffic signal system has been provided, which is truly automatic, dependent upon a novel operation incident to the well known tendency of motorists to travel in groups, with greater distances between the successive groups than occur between the vehicles of any one group. The operation is not, however, dependent upon the group traveling of vehicles, but operates according to the time interval with which the street switches are operated by vehicular traffic.

Various changes in the shape, size, and arrangement of parts may be made to the form of the operating circuit and details of the invention herein shown and described, without departing from the spirit of the invention or the scope of the claims.

I claim:

1. In a traffic signal system the combination with a pair of intersecting streets, a right of way indicating means for each of the streets at the intersection, a vehicle actuated switch in each street at each side of the intersection, a cam, switch means operated by the cam for operating the right of way indicating means, a control unit including a plurality of normally open switches, means adapted to close the switches after the passage of a predetermined interval of time including solenoids for tripping said means to prevent closing of the switches, said solenoids being normally inoperative, means electrically connecting the solenoids with the vehicle actuated street switches, including the switch means operated by the cam above mentioned, means for actuating the cam including an electro-magnetically operated clutch, and means connected between said normally open switches and the electro-magnet of the electro-magnetically operated clutch for causing an engagement of the clutch upon closing of a predetermined number of the normally open switches.

2. A traffic control system for the intersection of two streets with each street having two opposite approaches to the intersection, including in combination, electric right of way signals for the respective streets, cyclic switch mechanism having alternate switching positions for energizing the respective signals alternately, a vehicle actuated device in each approach of each street, a constantly rotating threaded central shaft, three other shafts arranged parallel and closely adjacent to the central shaft each such other shaft being slotted along its length collars fitted on said other shafts to slide freely along the length thereof and having projections engaging the slots of their respective shafts and adapted normally to engage also the thread of said central shaft to be driven along their respective shafts from one end toward the other over a time period and adapted to be disengaged from said central shaft and returned to said one end when their respective shafts are turned axially, contact members positioned to be actuated by the respective collars upon the latter having been driven from the end of the shafts for certain distances along such shafts by engagement with the central shaft, electromagnetic means adapted to be energized by actuation of the respective contact members to

turn the respective shafts and disengage the respective collars from said central shaft and including switch means operated by actuation of the respective contact members and maintained operated after each individual actuation thereof until all three contact members have been actuated to then shift said cyclic mechanism from one position to the other, switch means operated by said cyclic mechanism in being so shifted to de-energize said electromagnetic means again, and further switch means operated by said cyclic mechanism for connecting the electromagnetic means for two of said other shafts respectively to the respective vehicle actuated devices of the two approaches of one street while the right of way signal therein is energized to be energized momentarily by momentary actuation of their respective devices to return their associated collars momentarily to said one end of the respective shafts.

3. A traffic control system as in claim 2 and additionally including a fourth shaft, collar and contact member of the same character as said other three shafts, with the last named contact member positioned further along its shaft than the other contact members, and additional electromagnetic means energized directly by said last named contact member when the latter is actuated by its collar to shift said cyclic switch mechanism to said other position if it has not already been so shifted by the first mentioned electromagnetic means and also to turn said fourth shaft and collar to return the latter collar to the corresponding one end of its shaft.

4. A traffic control system for intersection of two streets with each street having two opposite approaches to the intersection, including in combination, right of way signals for the respective streets, cyclic operating means for said signals and having alternate operating positions to indicate right of way alternately to the respective streets, a vehicle actuated device in each approach of each street, two time controlled switch means initiated by said cyclic operating means in said one position and operating at definite times from such initiation, means associated with the cyclic operating means for connecting said additional time controlled switch means with the respective vehicle actuated devices in the respective approaches of said one street having right of way so as to reinitiate timing of the switch means for one approach by each actuation of the vehicle actuated device therein, and means including both said time switches and dependent on operation of both such switches at completion of their time periods to shift said cyclic operating means to its other position to indicate right of way to the other street.

5. A traffic control system as in claim 4 additionally including a maximum time controlled switch means initiated by said operating means in said one position and operating at a considerably longer time period than the other two time controlled switch means to shift said operating means to said other position if the latter has not already been so shifted by operation of said other time controlled switch means.

6. A traffic control system for the intersection of two streets with each street having two opposite approaches to the intersection, including in combination, right of way signals for the respective streets, cyclic operating means for said signals and having alternate operating positions to indicate right of way alternately to the respective streets, a vehicle actuated device in

each approach of each street, minimum time controlled switch means initiated by said cyclic operating means when the latter is in one position to indicate right of way to one street and operating at a minimum time from such initiation, two additional time controlled switch means initiated by said cyclic operating means in said one position and operating at a time from such initiation shorter than said minimum, means associated with the cyclic operating means for connecting said additional time controlled switch means with the respective vehicle actuated devices in the respective approaches of said one street having right of way so as to reinitiate timing of the switch means for one approach by each actuation of the vehicle actuated device therein, means including said minimum time switch and both said additional time switches and dependent on operation of all three of these switches at completion of their time periods to shift said cyclic operating means to its other position to indicate right of way to the other street.

5 10 15 20 25 30

7. A traffic control system as in claim 6 additionally including a maximum time controlled switch means initiated by said cyclic operating means in said one position and operating at a considerably longer time than said minimum from such initiation to shift said operating means to said other position if it has not already been so shifted by operation of the other time switch means.

8. A traffic control system for the intersection of two streets with each street having two opposite approaches to the intersection, including in combination, right of way signals for the respective streets, cyclic operating means for said signals and having alternate operating positions to indicate right of way alternately to the respective streets, a vehicle actuated device in each approach of each street, two time controlled switch means initiated by said cyclic operating means in said one position and operating at definite times from such initiation, means associated with the cyclic operating means for connecting said additional time controlled switch means with the respective vehicle actuated devices in the respective approaches of said one street having right of way so as to reinitiate timing of the switch means for one approach by each actuation of the vehicle actuated device therein, means including both said time switches and dependent on operation of both such switches at completion of their time periods to shift said cyclic operating means to its other position to indicate right of way to the other street, and means individual to each of said time switch means to maintain the respective switches operated upon and after completion of their respective time periods and until said shifting means operates, irrespective of further operation of the vehicle actuated means connected to the time switch means during such right of way on said one street.

9. A traffic control system for the intersection of two streets with each street having two opposite approaches to the intersection, including in combination, right of way signals for the respective streets, cyclic operating means for said signals and having alternate operating positions to indicate right of way alternately to the respective streets, a vehicle actuated device in each approach of each street, minimum time controlled switch means initiated by said cyclic operating means when the latter is in one position to indicate right of way to one street and operating at a minimum time from such initiation, two

additional time controlled switch means initiated by said cyclic operating means in said one position and operating at a time from such initiation shorter than said minimum, means associated with the cyclic operating means for connecting said additional time controlled switch means with the respective vehicle actuated devices in the respective approaches of said one street having right of way so as to reinitiate timing of the switch means for one approach by each actuation of the vehicle actuated device therein, means including said minimum time switch and both said additional time switches and dependent on operation of all three of these switches at completion of their time periods to shift said cyclic operating means to its other position to indicate right of way to the other street, and means individual to each of said time switch means to maintain the respective switches operated upon and after completion of their respective time periods and until said shifting means operates to shift said cyclic operating means to said other position.

10 15 20 25 30

11. A traffic control system for the intersection of two streets with each street having two opposite approaches to the intersection, including in combination, electric right of way signals for the respective streets, cyclic switch mechanism having alternate switching positions for energizing the respective signals alternately, a vehicle actuated device in each approach of each street, three time delayed switch means connected to have their timing initiated by said cyclic switch mechanism when the latter is in one position energizing the right of way signal on one street and adapted to operate their respective switches at completion of their respective timing, the first 40 of said switch means having a time period serving as a minimum for said cyclic switch mechanism in said one position, and the other two switch means having timing periods shorter than such minimum, switching means associated with said cyclic switching mechanism to connect said other two time delayed switch means to the respective vehicle actuated devices of the two approaches of said one street in said one position of said cyclic switch mechanism to reinitiate either one 45 of said other time switch means by each actuation of its connected vehicle actuated device to delay completion of its time period, and means including the switches of said three time switch means and operative only when all said three switches are concurrently operated to shift said cyclic switch mechanism to its other position to energize the right of way signal for the other street.

50 55 60 65 70

12. A traffic control system as in claim 11 additionally including a maximum time controlled switch means initiated by said cyclic operating means in said one position and operating at a considerably longer time than said minimum from such initiation to shift said operating means to said other position if it has not already been so shifted by operation of the other time switch means.
